CATALYTIC CRACKING

Davis Read, Jr., Chicago, Ill., assignor to Universal Oil Products Company, Chicago, Ill., a corporation of Delaware

Application January 28, 1942, Serial No. 428,452

1 Claim. (Cl. 196—52)

This invention relates to a process for the catalytic cracking of higher boiling hydrocarbon oils to form gasoline and other valuable products. It is more specifically concerned with catalytic cracking processes in which the catalyst is employed in powdered form and wherein the catalyst after contamination is regenerated by the oxidation of the carbonaceous deposits which reduce the activity of the catalyst.

It is old in the art to use cracking catalysts in the powdered form. In the processes heretofore disclosed, the catalyst has been used in suspension in a stream of the hydrocarbons undergoing conversion and in other cases the hydrocarbons in vaporous state have been bubbled through a relatively dense mass of the catalyst powder thus securing large weight ratios of catalyst to hydrocarbons in the conversion zone.

The process of my invention comprises a combination of suspended-catalyst cracking and cracking using a fluid catalyst operation. The high boiling oil is commingled with the powdered cracking catalyst and the mixture supplied to a heating coil under such conditions that a substantial quantity of the oil is vaporized. The extent of this vaporization depends upon the properties of the original charging stock and in the case of kerosene or a gas oil the vaporization might be practically completed. The cracking takes place during the vaporization process and thereafter, if desired, a reaction chamber may follow the heating coil in order to accomplish further cracking of the hydrocarbons. The reaction chamber is not an indispensable part of the process and may be omitted or included as desired. The reaction products from this catalytic cracking step are then subjected to a separation step in order to obtain a liquid fraction containing the catalyst in suspension and a lower boiling vaporous fraction.

The liquid fraction separated in the aforesaid step together with the suspended catalyst is supplied to a heating coil and a substantial quantity of the liquid is vaporized. The vaporization in this case may be aided by diluting the oil with steam or process gases. The heated oil and suspended catalyst is then supplied to a second reaction zone containing a relatively dense mass of catalyst powder, the gaseous hydrocarbons bubbling through the relatively dense mass of powder under conditions so regulated as to obtain the desired extent of catalytic cracking. It may be desirable to add highly heated steam or process gases to the powdered catalyst zone in order to supply the additional heat necessary for the vaporization of any residual quantity of liquid being

supplied to said zone. The products leaving the second reaction zone are entirely in the vaporous state and may be fractionated separately to recover the gasoline, normally gaseous products and unconverted higher boiling oil. If desired, however, the hydrocarbon conversion products from the second reaction zone may be commingled with the reaction products from the first cracking step and the mixture subjected to joint fractionation.

In one specific embodiment my invention comprises a process for the catalytic cracking of a higher boiling hydrocarbon oil to form gasoline which comprises charging said higher boiling hydrocarbon oil with suspended cracking catalyst into an elongated tubular reaction zone and there-in vaporizing a substantial portion of said oil and simultaneously and immediately thereafter cracking said oil to produce lower boiling products including gasoline, fractionating the products of said cracking step in commingled state with the products of a second catalytic cracking step hereinafter set forth to produce a vaporous fraction and a higher boiling liquid fraction containing the powdered catalyst in suspension, supplying said higher boiling liquid fraction and suspended catalyst to a heating zone to vaporize at least a substantial portion of said fraction and thereafter to a reaction zone containing a relatively dense mass of catalyst powder and bubbling the hydrocarbon vapors upward through said relatively dense mass of catalyst powder under conditions of temperature, pressure and time of contact regulated to produce substantial quantities of gasoline and fractionating the products from this second catalytic cracking step in commingled state with the products of the first catalytic cracking step as hereinbefore set forth.

The process of my invention is illustrated by the accompanying diagrammatic drawing and following specification which shows and describes one particular flow for accomplishing the process of my invention.

The charging stock plus a small quantity of catalyst equal to that lost due to incomplete separation methods is supplied to the system by way of line 1 and after passing through valve 2 enters pump 3 which discharges into line 4. A portion or all of the charging stock is used to scrub the gaseous products of regeneration leaving the powdered catalyst reactivating zone for the purpose of removing the catalyst suspended in said gases. The oil used as the scrubbing medium passes through valve 5 and is supplied to the top of column 6 wherein it is subjected to contact with the previously cooled gaseous products of regener-

ation. The oil with suspended catalyst is removed from scrubber 6 by way of line 7, controlled by valve 8. In case it is not desired to use all of the charging stock as a scrubbing liquid a portion may be by-passed around the scrubber being directed from line 4 through line 9, valve 10 to line 7. The mixture of oil and suspended catalyst powder then enters pump 11 which discharges through line 12, valve 13 to line 14 wherein it is commingled with the recycle fraction of unconverted higher boiling hydrocarbons and the mixture passed through valve 15 to heating coil 16.

The oil is heated in coil 16 by means of furnace 17 to a temperature which lies within the broad limits of about 600°-1100° F. but which under the usual conditions of operation is included in the more narrow limits of 750°-1000° F. The temperature to which the oil is heated depends upon the nature of the products desired, the higher the temperature, the greater the degree of unsaturation of the gasoline products. The pressure to which the oil is subjected also has a marked influence on the products, higher pressures producing a more saturated product having in general a greater susceptibility to increase in octane number with the addition of tetraethyl lead. The pressure in the heating coil may vary from the amount necessary to introduce the reaction product into the fractionation system by several hundred pounds per square inch at the entrance of the fractionating column. Under the usual and preferred conditions of operation a substantial portion and sometimes all of the oil is vaporized in the heating coil, the mixture of heated oil and catalyst being directed from coil 16 to line 18 wherein after passing through valve 19 it is supplied to reaction chamber 20. The purpose of this reaction chamber, the use of which is optional, is to permit further cracking if desired. In case it is desired to omit the reaction chamber the heated oil and catalyst is directed from line 18 to line 21 and after passing through valve 22 is supplied to line 23 wherein after passing through valve 24 it is supplied to vaporizing and separating chamber 25.

In order to accomplish the desired separation in chamber 25 it is necessary to reduce the temperature of the hydrocarbon vapors and this may be done by quenching the gases with the side cut removed from the fractionating column. Methods for accomplishing such quenching are well known in the art and need not be further described. The vaporous fraction separated in chamber 25 is removed by way of line 26, valve 27 and introduced to fractionating column 28. In this fractionating column the gasoline and normally gaseous products are removed as an overhead by way of line 29, controlled by valve 30. This overhead is then cooled, condensed and subjected to a stabilizing operation for the production of gasoline of the desired volatility. The olefinic constituents as well as the isoparaffinic constituents in the normally gaseous products may be converted to motor fuel by the well known processes of alkylation or polymerization. The products boiling above the range of gasoline are removed as a bottoms product from fractionating column 28 and enter line 31 and after passing through valve 32 enter pump 33 which discharges into line 14. In line 14 this recycle fraction of higher boiling products is commingled with the charging stock and supplied to heating coil 16 as hereinbefore set forth.

The liquid fraction obtained from separating chamber 25 containing the used catalyst in sus-

5 pension is removed by way of line 34 and after passing through valve 35 enters pump 36 which discharges through line 37, valve 38 into heating coil 39. It may be desirable to dilute this liquid fraction with steam or process gases to assist in the vaporization, these diluent gases being added to line 38 by way of line 40, controlled by valve 41. The hydrocarbon oil is heated in coil 39 by means of furnace 42 to a temperature from about 10 750° to about 1000° F. under pressure conditions such that at least part or all of the oil is vaporized. In the event that only partial vaporization is obtained in heating coil 39 it will be desirable to introduce a heat carrying medium into the stream of hydrocarbons. For this purpose steam or process gases may be used, these gases being introduced to the system by way of line 15 43 wherein after passing through valve 44 they are supplied to heating coil 45 so disposed as to receive heat from furnace 46. These heat carrying gases may be superheated to temperatures of the order of 1000-1100° F. and after being so heated enter line 47 and pass through valve 48 to line 49 wherein they are commingled with the high boiling oil and catalyst powder from heating coil 39. This mixture of high boiling oil and heat carrying gases, if the latter are used, pass through line 49 containing valve 50 after which they are commingled with catalyst powder obtained from the regeneration system, the mixture of catalyst, hydrocarbon reactants and heat carrying gases being introduced into reactor 51.

30 The catalyst in reactor 51 is in the form of a powder in a relatively dense mass, the hydrocarbon reactants and heat carrying gases being 35 bubbled through this dense mass in order to catalyze the desired cracking reactions. In order to secure uniform distribution of the reactants throughout the mass of powder, they are 40 caused to bubble through a distributing member 52 from which they flow upwardly through the relatively dense mass of powder which is kept in a state of constant agitation by the movement of the gases. The time of contact and proportion 45 of catalyst to gas is so selected that the desired degree of cracking takes place. The reaction products upon being disengaged from the upper surface 68 of the relatively dense mass of catalyst powder enter line 53 from which they are directed 50 to cyclone separator 54, the function of which is to separate the major portion of the entrained catalyst. The catalyst thus separated enters line 55 from which it is returned to the relatively dense phase present in the reactor. The hydrocarbon reaction products freed from a greater 55 portion of the entrained catalyst leave cyclone separator 54 by way of line 56 and pass through valve 57 to enter line 23 wherein it is commingled with the reaction products obtained from the first catalytic cracking zone.

60 The catalyst used in processing the hydrocarbons becomes contaminated by the deposition thereon of carbonaceous materials which reduces activity. In order to maintain the catalyst in uniform activity it is continuously removed from the reactor by being withdrawn from the dense phase through central conduit 58 from which it enters line 59, controlled by valve 60. The most common method of reactivating the carbonized catalyst is to oxidize the carbonaceous material by means of air or other medium of controlled oxygen content. Air is most conveniently used and is introduced to the system by way of line 61 and after passing through valve 62 enters 65 compressor 63 which discharges through line 64,

controlled by valve 65. After passing through valve 65 the air is commingled with the carbonized catalyst admitted to line 64 by way of line 59, the mixture of air and contaminated powder thereafter being introduced to regenerator 66. The general construction of the method of operation of the regenerator is similar to that of the reactor. The contaminated catalyst fills the regenerator to a level indicated by numeral 67 corresponding to the level 68 of the catalyst powder in the reacting zone. In order to prevent channelling, the air enters the dense mass of catalyst powder after passing through distributing member 86, the temperature, pressure and time of contact being so regulated that the desired oxidation reactions take place. The upward movement of the regenerating gases serves to maintain the relatively dense mass of catalyst powder in the state of agitation, the entire mass of powdered catalyst both in the regenerating zone and reacting zone having the appearance of a boiling liquid. The temperature prevailing within the regenerating zone may be within the approximate limits of 900-1150° F. This temperature must be controlled as excessive temperatures, such as for example, 1300-1400° F. has a marked deleterious effect on the life of the catalyst. The gaseous products of regeneration comprise principally carbon dioxide, water and the nitrogen present in the air and are disengaged from the relatively dense mass of catalyst powder, carrying with them a certain quantity of the catalyst in suspension. The mixture of gaseous products of regeneration and entrained catalyst leaving regenerating zone 66 by way of line 69 to enter cyclone separator 70 wherein a major portion of the catalyst powder is separated and returned to the regenerating zone by line 71 which dips into the dense phase of catalyst powder thus serving as a seal for the separator. The gases leaving the cyclone separator enter line 72 and after passing through valve 73 are cooled by indirect heat exchange in cooler 74. The function of this cooler is to reduce the temperature of the gases sufficiently so that they may be scrubbed with the hydrocarbon liquid in a subsequent step. The cooled gases leaving heat exchanger 74 enter line 75 and after passing through valve 76 are directed to scrubber 6. These gases carry with

them a certain quantity of catalyst powder in suspension which is removed by the scrubbing action of the liquid charging stock being supplied to said scrubber by way of line 4 as hereinbefore set forth. The gaseous products of regeneration leave scrubber 6 by way of line 77 and after passing through valve 78 are removed from the system.

The regenerated catalyst is continuously removed from regenerator 66 by means of the downtake 79 the upper end of which may extend to within a short distance of the upper surface of the catalyst powder. The dense mass of catalyst powder flows through this downtake 79 into line 80 wherein a portion is directed into line 82. After passing through valve 83, this portion of the catalyst powder is mixed with the charging stock in line 12, the mixture of catalyst and oil passing through line 14 wherein it is returned to the heater 17 as hereinbefore set forth. The remainder of the regenerated catalyst powder in line 80 passes through valve 81 from which it is directed to line 49 and thereafter supplied to reactor 51 wherein it is used in the fluid catalyst cracking step. Catalyst losses in the system may be made up by supplying catalyst in the form of a slurry to the system by way of line 84, controlled by valve 85, said line discharging into line 14 and thereafter into heating coil 16.

30 I claim as my invention:

A catalytic conversion process which comprises cracking hydrocarbon oil in a first reaction zone in admixture with a powdered cracking catalyst suspended in the oil, separating resultant vaporous products from residual liquid containing the powdered catalyst, introducing the mixture of residual hydrocarbons and catalyst into a second reaction zone containing a relatively dense mass of catalyst powder and bubbling the hydrocarbons through said mass under cracking conditions, removing the cracked vapors, substantially free of catalyst, from said second zone and fractionating and condensing the same, removing carbonized catalyst powder from the second reaction zone and regenerating the same, supplying a portion of the regenerated catalyst powder to said first zone and supplying another portion thereof to said second zone.
